UNITED STATES PATENT OFFICE.

JOSEPH W. DAWSON, OF AUBURN, ALABAMA.

SEED-PLANTER.

SPECIFICATION forming part of Letters Patent No. 291,579, dated January 8, 1884.

Application filed March 14, 1883. (No model.)

To all whom it may concern:

Be it known that I, JOSEPH W. DAWSON, a citizen of the United States, residing at Auburn, in the county of Lee and State of Alabama, have invented a new and useful Seed-Planter, of which the following is a specification, reference being had to the accompanying drawings.

This invention relates to seed-planters; and it consists in certain improvements in the construction of the same, which will be herein-after fully described, and particularly pointed out in the claims.

In the drawings hereto annexed, Figure 1 is a perspective view. Fig. 2 is a top view. Fig. 3 is a vertical transverse section. Fig. 4 is a detail view in perspective of the seed box or drum, with parts broken away for the purpose of showing the construction more clearly. Fig. 5 is a detail view of the central wheel or disk. Fig. 6 is a detail view of the central partition.

The same letters refer to the same parts in all the figures.

A in the drawings designates the frame, which consists of the sides B B, connected by transverse braces C, D, and E, the ends of which are screw-threaded, and provided with spacing-nuts F and clamping-nuts G. The front ends 30 of the side pieces, which are to be made of heavy strap-iron, are bent inwardly and forwardly, as at H, and connected by a bolt, I. Between the front ends, H, which form the tongue, is clamped the standard J of the furrow-opener K, for the vertical adjustment of which suitable provision is made. Upon the ends of the rear brace, E, are secured vertical braces L L, the lower ends of which carry the coverer M. The lower ends of the bars or 40 braces L are connected by inclined braces N with the ends of the central frame-brace, D. Handles O O are secured to the ends of the brace D and to the upper ends of the vertical bars L, as shown. In this manner a strong 45 and durable and at the same time a light and neat frame is constructed at a small expense. The central frame-brace also serves as an axle upon which the seed box or drum P is journaled, as shown. The said drum consists, essentially, of a central wheel or disk and two sides or "heads," the construction and arrange-

ment of which I shall now proceed more fully to describe.

Q designates the central disk or wheel, which is a flat ring of suitable dimensions, having a 55 diametrical brace, R, through which the axle D passes.

S S are the heads, which consist of cylinders closed at their outer ends and provided at their inner ends with flanges T and lugs U, to receive the transverse bolts V, by means of which they are secured to the center disk, washers W being interposed, so as to leave any desired space between the center disk and the inner open ends of the heads. When the device is 60 to be used as a combined seed-planter and fertilizer-distributer, a thin partition-plate, X, is interposed between the disk Q and one of the heads. The said plate X is provided with a radial slot, Y, in order to enable it to be 65 readily adjusted or removed, as may be required. When the plate is in position, the said slot registers with one end of the diametrical brace R, thus making the separation between the two heads or ends complete. The 70 heads or ends S are provided with hinged doors Z, through which they may be readily filled when required.

A² A² are segmental plates hinged upon the transverse bolts V, adjoining one side of the 80 plate or disk Q. The free ends of the said segmental plates are adjustable by set-screws B², pressing or bearing against the disk Q, for the purpose of regulating the feed.

In operation the drum P revolves, and the 85 seed and fertilizing material drops out through the spaces between the inner open ends of the heads S and the disk Q into the furrow made by the opener K, and is covered by the coverer M.

I claim as my invention and desire to secure by Letters Patent of the United States—

1. The combination of the side pieces, B B, the transverse braces C D E, the vertical bars secured upon the ends of the rear brace and 95 carrying the coverer, the diagonal braces connecting the lower ends of the vertical bars with the ends of the center brace, and the handles secured to the ends of the center brace and to the upper ends of the vertical bars, as set forth. 100

2. The combination of the side pieces, B B, the transverse connecting-braces C, D, and E,

- all of which are provided with spacing-nuts F and clamping-nuts G, and the revolving seed box or drum journaled upon the center brace, as set forth.
- 5 3. The combination of the central disk or ring, the cylindrical heads bolted to the sides of the same, the interposed washers, and a detachable partition-plate secured between the center disk and one of the heads, as set forth.
- 10 4. The combination of the central disk or ring having a diametrical brace journaled upon the axle D, the cylindrical heads, and the detachable partition-plate having a radial slot, as and for the purpose set forth.
- 15 5. The combination of the center ring, the cylindrical heads having lugs at their inner ends, the transverse connecting-bolts, and the segmental feed-regulating plates pivoted upon said bolts adjoining one side of the center plate, and provided at their free ends with set-screws 20 bearing against the said center plate, as set forth.

In testimony that I claim the foregoing as my own I have hereto affixed my signature in presence of two witnesses.

JOSEPH WASHINGTON DAWSON.
